(57) **CLAIM**

The ornamental design for a cordless nailer, as shown and described.

DESCRIPTION

FIG. 1 is a top and right-side perspective view of a cordless nailer showing our new design;

FIG. 2 is a top and left-side perspective view thereof;

FIG. 3 is a right-side elevation view thereof;

FIG. 4 is a left-side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate portions of the cordless nailer that form no part of the claimed design.
